(57) **CLAIM**

The ornamental design for a beacon light, as shown and described.

DESCRIPTION

FIG. 1 is an isometric front view of a beacon light showing the new design;

FIG. 2 is a front view of the design of FIG. 1;

FIG. 3 is a back view of the design of FIG. 1;

FIG. 4 is a right side view of the design of FIG. 1;

FIG. 5 is a left side view of the design of FIG. 1;

FIG. 6 is a top view of the design of FIG. 1; and,

FIG. 7 is a bottom view of the design of FIG. 1.

The broken line showing of elements comprised of even length dashes is included for the purpose of illustrating portions of the beacon light and forms no part of the design. The broken lines comprised of alternating shorter and longer dashes in FIGS. 1, 2, 4, and 6 immediately adjacent to the shaded area represent unclaimed boundaries of the design.
